UNITED STATES PATENT OFFICE.

ARTHUR L. BALDWIN, OF DETROIT, MICHIGAN, ASSIGNOR TO DETROIT STEEL PRODUCTS COMPANY, OF DETROIT, MICHIGAN, A CORPORATION OF MICHIGAN.

SPACING-CLIP FOR DOUBLE-Pane WINDOWS.

1,129,839.

Specification of Letters Patent. Patented Mar. 2, 1915.

Application filed February 5, 1914. Serial No. 816,703.

To all whom it may concern:

Be it known that I, ARTHUR L. BALDWIN, a citizen of the United States of America, residing at Detroit, in the county of Wayne and State of Michigan, have invented certain new and useful Improvements in Spacing-Clips for Double-Pane Windows, of which the following is a specification, reference being had therein to the accompanying drawings.

The invention relates to windows of that type provided with double glazing and in which parallel window panes are secured to the sash to form an air space therebetween.

It is the object of the present invention to provide a simple device for quickly positioning and securing the panes in properly spaced relation, the construction being particularly adapted for use in connection with metallic window sashes.

In the drawings: Figure 1 is a section through one of the sash bars and double panes, showing my improvement applied thereto; Fig. 2 is a perspective view of the clip; and Figs. 3 and 4 are views similar to Figs. 1 and 2 showing a modified construction.

A is one of the sash bars provided with the usual ledge or shoulder B forming the bearing for the window pane and the web portion C extending at right angles thereto.

D is a clip preferably formed of sheet metal and provided with a spacing portion E, a hook portion F at one side thereof and a tongue portion G at the opposite side thereof. As specifically shown, the portion E is formed by a U-shaped bend of the sheet metal, the portion F by a reversely-bent U and the portion G by a flat projection in the plane of the bottom F' of the hook portion F. The portion G is also preferably tapered toward its outer end, and is prefer-

ably notched or otherwise weakened, as indicated at H, so as to facilitate forming an angle bend therein.

In use, the glass pane I, which lies adjacent to the shoulder B, is engaged with the hooked portions F of a plurality of the clips D suitably spaced about the pane, and the latter is then placed in the window sash and secured in position by any suitable means. A second pane J is then placed in the sash against the spacing portion E, after which the tongue G is bent inward to form a hook, as indicated at K, Fig. 1, which secures the two panes in fixed relation to each other. The whole is then secured in position by any suitable construction of clip (not shown).

In the modified construction shown in Figs. 3 and 4, the bendable tongue G is dispensed with and the clip is formed merely with the reversely-bent U-shaped portions E and F. With this construction the portion E forms a spacer which is secured by the hook portion F to the first pane and the second pane is secured in position by any suitable means (not shown).

What I claim as my invention is,—

A double glazing clip for window sashes, comprising a sheet metal blank bent to form a spacing portion of U-shaped cross section, a reversely-bent U-portion at one side thereof engageable with one of the window panes, and a tongue portion at the opposite side in the plane of the bottom of said last-mentioned U-portion and bendable to form a hook for the second pane.

In testimony whereof I affix my signature in presence of two witnesses.

ARTHUR L. BALDWIN.
